[57] CLAIM

The ornamental design for a combined flint dispenser and screwdriver, substantially as shown and described.

DESCRIPTION

FIG. 1 is a top plan view of a combined flint dispenser and screwdriver incorporating my design;

FIG. 2 is an end elevational view;

FIG. 3 is a front elevational view;

FIG. 4 is an end elevational view, opposite to that of FIG. 2;

FIG. 5 is a bottom plan view; and

FIG. 6 is a rear elevational view.

FIG. 1.

FIG. 2.

FIG. 3.

FIG. 4.

FIG. 5.

FIG. 6.
